UNITED STATES PATENT OFFICE.

LOUIS B. GOLDBERG, JACOB M. GOLDBERG, NATHAN GOLDBERG, AND WILLIAM GOLDBERG, OF DENVER, COLORADO.

BURNER CONSTRUCTION FOR GASOLINE CAMP STOVES.

Application filed January 3, 1922. Serial No. 526,670.

To all whom it may concern:

Be it known that we, LOUIS B. GOLDBERG, JACOB M. GOLDBERG, NATHAN GOLDBERG, and WILLIAM GOLDBERG, citizens of the United States, and residents of the city and county of Denver, State of Colorado, have invented certain new and useful Improvements in Burner Constructions for Gasoline Camp Stoves, of which the following is a description, reference being had to the accompanying drawings, which form a part hereof.

The object of the invention is to provide a construction of the class stated which shall be novel and at the same time highly efficient in operation and cheap to manufacture.

Briefly the invention comprises a burner having a valve, preferably cylindrical, by means of which the flow of generated gas may be regulated from full feed to closed position with a limited amount of movement. The burner carries a single spreader plate which is formed merely by shearing to provide radial slits which form an opening directed laterally over the adjacent portion of the plate in each instance. A grate positioned above the burner is supported directly by the walls of the casing within which the burner is carried.

In the drawings, wherein certain embodiments of the invention are disclosed,

Fig. 1 is a plan of the burner showing the present valve;

Fig. 2 is a section therethrough taken on line 2—2 of Fig. 1;

Fig. 3 is a longitudinal section as indicated by line 3—3 of Fig. 1 showing the spreader plate, grate and mounting within the casing;

Fig. 4 is a plan of the spreader plate;

Fig. 5 is a sectional detail on line 5—5 of Fig. 4;

Fig. 6 is a plan showing a modified form of grate mounting; and

Fig. 7 is an enlarged sectional detail of the valve showing a slight modification over that of Fig. 3.

The casing within which the burner is mounted is provided with a bottom wall 10 and side walls 12 upon any of which the grate 24 may be supported, the burner cup 14 resting upon said bottom wall 10. The cup 14 is provided with a preferably integral manifold 15 into which gas generated from gasoline by any suitable means (not shown)

is introduced for feeding into the chamber

within the cup. The upper edge of the cup 14 carries a spreader plate 16 having an annular flange 18 to insure proper positioning, the center of the plate 16 being depressed at 20 to receive the bottom of a priming or generating pan or cup 22 provided at the center of the grate 24. Plate 16 is provided with an aperture 25 in the center of depression 20 for the reception of a retaining screw 26 threaded into a boss 28 mounted upon the manifold 15 so that said plate 16 may be secured in position. Or, as indicated in Fig. 7, the depression 20 of plate 16 may be used directly as a priming cup.

Spreader plate 16 is formed by shearing the same at a number of places to form a plurality of radially disposed slits at 30, the metal at one side of each slit being forced slightly out of the plane of the plate to form slightly offset fins 32, best seen in Fig. 5, and thereby providing elongated discharge openings or slots 34 which direct the fuel gas laterally over the adjacent portions of the plate instead of directly upward as is usual. In this manner the flame is given a slight swirling motion so that the flame from any one slot or opening 34 will be driven toward and across the adjacent opening at one side so as to insure re-ignition of gas issuing therefrom in the event that such should be blown out as by the wind or the like. Thus it will be impossible to blow out the entire flame on the burner except by a very strong wind.

For the purpose of controlling the flow of gas to the chamber within the cup 14, the manifold 15 is machined to provide a cylindrical bore which provides a neat fit for a sleeve valve 36. The upper portion of the manifold is provided with an aperture or discharge port 35 with which a similar aperture 38 in sleeve 36 is adapted to register. The outer end of sleeve 36 also is neatly fitted in the casting forming the cup 14 and manifold 15, and is closed as by means of a plug 40 into which a stem 42, having a manipulating head 44, is threaded or otherwise secured. In this manner the port 35 may be quickly opened or closed either by sliding the sleeve 36 a short distance longitudinally or by rotating it a quarter turn or less through the medium of the stem 42 which projects beyond the casing. Within these narrow limits there is found all the range required for complete control of the

burner from wide open position to closed position. The neat fit of the sleeve within the manifold permits easy and sure adjustment to any desired position. This form, 5 which permits adjustment by either rotation or reciprocation, is shown in Fig. 3.

In Fig. 7, a similar form is shown, but with the difference that the sleeve 36 is provided with an annular groove 45 which receives the end of the screw 26, said screw being slightly longer in this form than in the other so as to enter said groove. Thus the valve 36 may be rotated for adjustment, but is held by the screw 26 against movement 15 longitudinally.

The grate 24 is supported above the burner by either the side walls 12 or bottom wall 10 of the casing, and if desired the priming pan 22 may fit in the depression 20 of the plate 16 and over the head of screw 26. As shown in Fig. 3, the means for supporting the grate 24 consists in a plurality of legs 50 whose lower ends are shouldered for engagement with the bottom of the casing and to provide fingers which project through apertures in the bottom wall of the casing, said fingers being slightly offset or bulged at 52, if desired, so that the parts will be slightly sprung when moved into position for retaining the operative relation thereof. In the form of Fig. 6, the grate 24 is provided with a plurality of laterally extending legs 60 also shouldered and adapted to engage the side walls 12 of the casing, the 35 ends of the legs having fingers to project through apertures in said walls, and the walls being sprung to permit positioning of said legs and fingers. Thus the walls of the casing itself are made to support the grate 40 in proper position over the burner and the fingers serve as braces to strengthen the walls.

This construction is very desirable for portable camp stoves. The grates are easily 45 mounted upon the casing, which is of sheet metal, and may be securely retained thereby. Thus, the grates may be employed either to assist in retaining or to solely retain the burner or burners, two of which are usually 50 used. The spreader plate insures a continuously burning flame, and the valve permits quick control movement from one position to another. The spreader plate also has advantages from the manufacturing standpoint, inasmuch as it is necessary merely to shear or slit the plate and strike up the fins 55 32 without having to cut out any metal as would be the case in forming ordinary slots cut in the flat sheet.

60 We claim:

1. A gas burner comprising a burner cup and a spreader plate mounted thereon, the

said plate having a central depression and being inwardly flanged at its outer edge to engage the upper edge of the wall of the 65 cup, the zone between the depression and the flange having a multiplicity of radial slots, the material of the plate being offset outwardly adjacent the slots to form lips for directing the flame laterally. 70

2. A gas burner comprising a burner cup and a spreader plate, the latter having a central depression and an inwardly projecting flange at its outer edge where it engages the cup, the zone between the depression and the 75 flange having a plurality of radial slots, the material of the plate being offset outwardly adjacent the slots to form lips for directing the flame laterally, the slots being of uniform width throughout their length. 80

3. A spreader plate having a central depression and being inwardly flanged at its outer edge in the direction of the depression, the zone between the depression and the flange having a multiplicity of radial slots, 85 the material of the plate being offset outwardly adjacent the slots to form lips for directing the flame laterally. 90

4. A burner for camp stoves, having a cup and a spreader plate mounted thereon, said plate having a central depression and being inwardly flanged at its outer edge to engage the upper edge of the wall of the cup, the zone between the depression and the flange having a plurality of radial slits, the material of the plate being offset outwardly adjacent one side of said slits to form slots, the width of said slots being equal along their entire length. 95

5. A burner for camp stoves having a cup 100 and a spreader plate, the plate having a central depression and having its outer edges inwardly flanged a plurality of radially disposed elongated openings formed by shearing the plate and offsetting the same 105 at one side only of each opening so as to retain all the stock of the plate adjacent said openings, each opening being of uniform width and the offset edges being all in the same plane. 110

6. A burner for camp stoves comprising a burner cup, a spreader plate secured thereto, said plate having a depression, a grate above said plate and having a depending member positioned in said depression, and legs on the grate for supporting the same independently of the cup and plate. 115

In testimony whereof, we affix our signatures.
